UNITED STATES PATENT OFFICE

2,632,900

BOAT HANDLING APPARATUS

Charles A. Voigt, Deer River, Minn.

Application October 13, 1950, Serial No. 189,985

5 Claims. (CL. 9—30)

1

The present invention relates to improvements in boat handling apparatus and more particularly to the type of device which is adapted to pivot a boat from its floating position to a substantially overturned position to empty the water collected therein from rainstorms and whereby the boat may be lifted from the water for painting or other operations.

An object of the present invention is to provide an improved apparatus whereby a boat may be lifted from the water and pivoted to a position whereby the bottom of the boat is substantially upstanding for emptying the water in the boat or for painting the underside, etc.

A still further object of the present invention resides in the provision of novel means whereby when the boat is to be pivoted upwardly and out of the water, a two-way motor is actuated for operating a winch and pulley arrangement, a pair of cables attached to the pulley arrangement being adapted to engage the underside of the boat for lifting the same.

Still another object of the present invention resides in the provision of a novel means engageable by the boat when pivoted to its uppermost position whereby engagement of the boat with the means opens the electrical circuit to the motor operating the winch whereby the same will be deactuated.

Another object of the present invention resides in the provision of means for normally holding the cables in their boat receiving position.

A still further object of the present invention resides in the novel frame for supporting the means of the present invention, the frame being mounted on a pair of floatable runners whereby the entire structure of the present invention may be floated to the position where it is to be employed, at which point it may be submerged.

Another object of the present invention resides in the novel runners whereby the same may be slid along the mud and will be supported by the broad area afforded by the runners during the lifting operation of the boat.

Various other objects and advantages will become apparent from the detailed description to follow. The best form in which I have contemplated applying my invention is clearly illustrated in the accompanying drawings, wherein:

Figure 1 is a perspective view of the entire structure of the present invention in its boat receiving position;

Figure 2 is a horizontal longitudinal sectional view taken substantially along the plane of line 2—2 of Figure 1;

2

Figure 3 is an end elevational view of Figure 1;

Figure 4 is a vertical sectional view taken substantially along the plane of line 4—4 of Figure 1; and,

Figure 5 is a diagrammatic view of the circuit diagram.

Referring more particularly to the drawings, wherein like numerals designate like parts throughout, the numeral 10 designates generally the frame, the numeral 12 designates generally the operating means and the numeral 14 designates generally the pulley and cable arrangement mounted on the frame 10.

The frame 10 is of parallelepiped form having a pair of rectangular open end frames which are comprised of a pair of upstanding bars 16 and 18 and transversely extending bars 20 and 22 joining the upper and lower portions of the upstanding bars. Longitudinally joining the end portions of the frame are a plurality of elongated bars 24, 26, 28 and 30.

The entire frame 10 is mounted on a pair of runners 32 and 34 which receive the lower ends of the upstanding bars 16 and 18. The runners 32 and 34 are floatable since they are formed of hollow construction having upstanding walls 36 and 38 and 40 and 42.

The actuating means 12 for operating the present invention is comprised of a two-way electric motor 44 which drives the pulley 46. The motor 44 is mounted on the platform 48 which is secured to the elongated bar 28. Also mounted on the platform 48 is the winch 50 which is operatively connected to the motor 44 by means of the pulley 52 and belt 54 which passes over the pulleys 46 and 52. At 56 is the handle for operating the two-way switch for the motor 44.

The cable and pulley arrangement 14 is comprised of a first cable 58 which is secured at one end to the winch 50 for winding thereon and has an intermediate portion passed over the pulley 60 which is supported by the cross bar 62 mounted on the upper sides of the elongated walls 24 and 26. A pair of supporting cables 64 and 66 have their outer ends connected to the ring 68 secured to the standard 16 by means of the eyelet 70. The inner ends of the cables 64 and 66 are secured to the ring 72 by means of their eyelets 74. The lower end of the first cable 58 is also connected to the ring 72.

A means is provided for normally holding the pair of supporting cables 64 and 66 in the position shown in Figure 1, and that means is comprised of the cable 76 which passes over a first pulley 78 mounted on the bar 30, a second pulley

80 mounted on end of the cross bar 62, and the free end of the cable 76 has a weight 82 connected thereto.

As seen best in Figure 4, a normally closed switch 84 is interposed in the conductor wire 86 and 66' for supplying power to the switch of the motor 44. A plunger 88 extends from the switch housing 84 and is engageable by the pivot element 90 which is hingedly attached to the bar 28 by means of the hinge 92.

From the foregoing description, taken in conjunction with the drawings, it is believed that a device has been provided which is simple in operation and which will accomplish all of the objects hereinabove set forth. When it is desired to perform an operation on the boat 100, it is moved through one open end of the frame 10 and over the cables 64 and 66. Next the switch handle 56 is moved to actuate the motor 44 to operate the winch for winding the first cable 58 and raising the cables 64 and 66 with the boat 100. The boat will pivot against one side of the frame and when it reaches its uppermost position, it will engage the switch lever 80 to effect opening of the switch 84 whereby the motor 44 will be deactuated. When it is desired to relower the boat, the switch 57 is actuated and the switch 56 is reversed, thereby unwinding the cable on the winch and lowering the cables supporting the boat.

In the circuit diagram of Figure 5 the operation will be more readily understood. The switch 85 will be opened when the boat reaches its uppermost position but the break in the circuit for the switch 56 may again be completed by closing the manually operated switch 57.

Having described the invention, what is claimed as new is:

1. A boat manipulating apparatus comprising a frame of parallelepiped form open to permit the entry and exit of a boat through its ends, said frame including upright corner members, a pair of longitudinally extending runners receiving the lower ends of said upright corner members, a two-way motor and winch mounted on one side of said frame, a first cable received on said winch, a pair of boat engaging cables connected to the upright corner members of the one side of the frame on which the winch is mounted, said first cable having its outer end connected to said boat engaging cables for raising and lowering the same in response to actuation of the motor.

2. A boat manipulating apparatus comprising a frame of parallelepiped form open to permit the entry and exit of a boat through its ends, said frame including upright corner members, a two-way motor and winch mounted on one side of said frame, a first cable received on said winch, a pair of boat engaging cables connected to the upright corner members of said one side of the frame, said first cable having its outer end connected to said boat engaging cables for raising and lowering the same in response to actuation of the motor, a cross bar disposed transversely of the frame intermediate the ends thereof, a pulley mounted on said cross bar intermediate the sides of said frame, said first cable passing thereover for connection to said pair of cables.

3. A boat manipulating apparatus comprising a frame of parallelepiped form open to permit

the entry and exit of a boat through its ends, a two-way motor and winch mounted on one side of said frame, a first cable received on said winch, a pair of boat engaging cables connected to the ends of said one side of the frame, said first cable having its outer end connected to said boat engaging cables for raising and lowering the same in response to actuation of the motor, a pulley mounted on the other side of said frame adjacent the lower portion thereof, a cable passing through said pulley and connected to said pair of cables for pulling said pair of cables to the boat receiving position.

4. A boat manipulating apparatus comprising a frame of parallelepiped form open to permit the entry and exit of a boat through its ends, a two-way motor and winch mounted on said frame, a first cable received on said winch, a pair of boat engaging cables connected to the ends of one side of the frame, said first cable having its outer end connected to said boat engaging cables for raising and lowering the same in response to actuation of the motor, a cross bar disposed transversely of the frame adjacent the top thereof, said cross bar projecting laterally from the side opposite the side to which the pair of cables are connected, a pulley mounted on said cross bar intermediate the sides of said frame, said first cable being entrained over said pulley, a second pulley mounted adjacent the lower portion of the side of the frame opposite to the side to which the pair of cables are connected, a third pulley mounted on the extending end of said cross member, a control cable connected to said pair of cables and entrained through said second and third pulleys, a counterweight secured on the outer end of said control cable.

5. A boat manipulating apparatus comprising a frame of parallelepiped form open to permit the entry and exit of a boat through its ends, said frame including upright corner members, longitudinally extending bars joining said corner members, a two-way motor and winch mounted on said frame, a first cable received on said winch, a pair of boat engaging cables connected to the upright corners of one side of the frame, said first cable having its outer end connected to said boat engaging cables for raising and lowering the same in response to actuation of the motor, and a normally closed switch mounted on one of said corner members to which said pair of cables are connected, a switch actuating member pivotally mounted on a longitudinally extending bar, said actuating member extending across the path of movement of a boat raised by said cables, said switch being opened by engagement of the boat against said member for deactuating the motor.

CHARLES A. VOIGT.
